UNITED STATES PATENT OFFICE.

JACOB G. MISSIMER, OF PHILADELPHIA, PENNSYLVANIA.

RIB FOR UMBRELLAS.

SPECIFICATION forming part of Letters Patent No. 605,113, dated June 7, 1898.

Application filed January 22, 1898. Serial No. 667,552. (No model.)

To all whom it may concern:

Be it known that I, JACOB G. MISSIMER, a citizen of the United States, residing in the city and county of Philadelphia, State of Pennsylvania, have invented a new and useful Improvement in Ribs for Umbrellas, &c., which improvement is fully set forth in the following specification and accompanying drawings.

10 Heretofore ribs of umbrellas and parasols have been provided with eyes which are formed by flattening the ends of the ribs and piercing the same, said eyes receiving the wire which connects them with the notch or notched collar on the stick or staff and forms the axis of the ribs; but such eyes and ends 50

rust and corrode, lose their strength, and break in short order.

My invention is designed to remedy such 20 objectionable features; and it consists in providing a rib of the character stated with a cylindrical-shaped eye formed by bending or turning the rib back on itself, so as to produce the eye, the same being integral with the rib, without being pierced, as heretofore, there being a spirally twisted or coiled neck 55

between the eye and body of the rib, the same corrugating and strengthening said neck, so that its durability is increased.

30 Figure 1 represents a perspective view of a portion of an umbrella-rib embodying my invention. Fig. 2 represents a side elevation of the same.

Similar letters of reference indicate corresponding parts in the figures.

Referring to the drawings, A designates a portion of a rib the upper end of which is turned or twisted, as at B, and the metal turned back on itself, preferably in a curved 40 direction, producing a hollow cylinder which constitutes an eye, as shown at C, the curve extending at a right angle to the longitudinal direction of the rib and being adapted to receive the wire D which connects several 45 ribs employed with the notch or notched collar in the stick, it being noticed that the metal is not pierced to form said eye and so possesses increased strength and greater durability, and it also provides a broad bearing-

surface on the wire, so that it turns true in 50 its opening and closing motions, and also presents enlarged side surfaces which rest freely against the walls of the notches of the collar, so that side wobbling of the ribs within said notches is prevented.

55 In the operation of forming the twist B, which constitutes a neck intermediate of the body of the rib and the eye, it deflects the fiber of the metal at the relative place from a right line into a spiral one or a spiral corrugation 60 and in a measure upsets the metal, thus rendering the same more compact, and consequently produces a neck of great strength and durability.

As a neck is required between the body of 65 the rib and the eye, so that the rib may have the greatest freedom of motion in the opening and closing motions of the umbrella without having the end of said body contact with the bearing of the eye, said neck is necessarily formed by thinning out the metal at the end of the body and then bending a portion of the same into eye form, leaving a portion unbent, which constitutes the neck proper, which portion, *per se*, is weak; but the 70 same is twisted or converted into a spiral, which has the advantages above stated.

75 Of course the lower end of what is known as the "stretcher" of an umbrella or parasol may have an eye thereon constructed similarly to that hereinbefore described as on the upper end of a rib, as I consider the invention broad enough to include either of said parts of an umbrella-frame, although it more particularly refers to a rib.

80 Having thus described my invention, what I claim as new, and desire to secure by Letters Patent, is—

85 A rib of the character stated, having thereon a cylindrical eye, the same extending at a right angle to the longitudinal direction of the rib, and a coiled neck intermediate of said eye and the body of the rib.

JACOB G. MISSIMER.
